UNITED STATES PATENT OFFICE.

JAMES WILSON, OF WEST ALLIS, WISCONSIN, ASSIGNOR TO ALLIS-CHALMERS MANUFACTURING COMPANY, OF MILWAUKEE, WISCONSIN, A CORPORATION OF DELAWARE.

LIQUID COOLER.

Application filed October 2, 1920. Serial No. 414,245.

To all whom it may concern:

Be it known that JAMES WILSON, a citizen of the United States, residing at West Allis, in the county of Milwaukee and State 5 of Wisconsin, has invented a certain new and useful Improved Liquid Cooler, of which the following is a specification.

This invention relates in general to improvements in the art of cooling substances, 10 and relates more specifically to improvements in the construction and operation of devices for cooling liquid such as oil.

An object of the invention is to provide a cooling device which is simple in construction 15 and efficient in operation. Another object of the invention is to provide a compact automatic cooler for liquid such as oil.

Some of the more specific objects of the invention are as follows:

20 To provide an automatic liquid cooling device which is relatively compact in structure and in which the liquid is most effectively presented to the cooling surfaces.

To provide a cooler which is exceedingly 25 simple in construction and which may be readily assembled and dismantled.

To provide a cooling device for oil which may be readily inserted in a closed lubricant 30 circulating system, and which is adapted to utilize liquid as a cooling agency.

To provide other improvements in the details of construction and operation of liquid coolers, which will permit manufacture 35 thereof at minimum cost and which will produce maximum efficiency in operation.

A clear conception of an embodiment of the invention and of the operation of the device, may be had by referring to the drawing accompanying and forming a part 40 of this specification, in which like reference characters designate the same or similar parts in the various views.

Figure 1 is a central vertical section through an oil cooler.

45 Figure 2 is a top view of the oil cooler.

Figure 3 is a transverse horizontal section through the oil cooler, the section being taken along the line III—III of Figure 1 looking in a downward direction.

50 The cooling device comprises in general an outer tubular casing 2, an inner tubular member 11 mounted centrally within the casing 2, and a pair of helical coiled pipes 9, 10 located within the outer casing 2 and sur-

rounding the inner member 11. The outer 55 casing 2 has its lower extremity closed by means of a screw cap 13 and is provided at its upper extremity with a flange 3 to which a cap plate 4 is detachably secured by means of cap screws 14. The inner tubular member 11 is secured to the central portion of the cap plate 4 and extends downwardly within the casing 2. The lower extremity of the inner member 11 is spaced from the lower cap 13 of the casing 2. An oil inlet pipe 65 7 secured to the cover plate 4, communicates with the upper inner portion of the member 11, while an oil discharge pipe 6 secured to the cover plate 4 communicates with the upper 70 end of the space within the casing 2 and surrounding the member 11. The coiled pipes 9, 10 are located within the space between the casing 2 and the inner member 11, and are staggered, that is, the inner pipe 9 is disposed within the helical space between 75 the coils of the outer pipe 10. These pipes 9, 10 are assembled by screwing the inner pipe 9 into the outer pipe 10, such assembling being permitted by the formation of the coils with equal pitch or distance between 80 coils. The lower extremities of the pipes 9, 10 are connected by means of a bent pipe 12, which may be soldered or otherwise detachably connected to the coiled pipes. The upper extremity of the inner pipe 9 communicates 85 with a cooling water pipe 8 which is secured to the cover plate 4. The upper extremity of the pipe 10 communicates with a cooling water pipe 5 which is also connected to the cover plate 4.

90 During normal operation of the cooler, the oil or other liquid which is to be cooled is admitted to the interior of the central tubular member 11 through the central inlet pipe 7 and flows downwardly within the tubular member 11 to the bottom of the casing 2. The heated oil thus admitted then spreads and flows upwardly, in contact with the surfaces of the coiled pipes 9, 10. Cooling water or other agency is admitted 95 through one of the pipes 5, 8 to the interior of the pipes 9, 10, this cooling water being discharged from the other pipe 5, 8. As the oil flows upwardly through the space between the tubular member 12 and the casing 2, it is compelled to assume a circuitous path 100 about and between the staggered coils of the pipes 9, 10, thereby quickly and effectively 105

reducing the temperature of the oil to substantially the temperature of the cooling agency admitted through a pipe 5, 8. The cooled oil after reaching the upper extremity of the casing 2 is delivered from the cooler through the oil discharge pipe 6.

It will thus be noted that oil or other fluid admitted through the inlet pipe 7 automatically has its temperature changed to substantially that of the agency in the coils 9, 10, and is delivered from the apparatus through the discharge pipe 6. Due to the staggered arrangement of the coiled pipes 9, 10 the oil or other fluid treated is forced to flow in direct contact with practically all portions of these coils, thereby utilizing the cooling changing agency with best efficiency. It will also be obvious that the oil may be admitted through an opening in the lower cap 13 and caused to flow directly to the pipes 9, 10, without necessitating passage through the member 11.

The cooler may be readily dismantled by releasing the cap screws 14 whereupon the outer casing 2 may be withdrawn from the pipes 9, 10. The pipes 9, 10 may be disconnected from the cover plate 4 and from the connecting pipe 12, whereupon the inner pipe 9 may be removed endwise by rotating the same relatively to the outer pipe 10. It will be noted that the device may be assembled by reversing these several operations and that the assembled structure provides a compact and highly efficient heat transferring device. While the description refers specifically to the cooling of oil and to the utilization of water as a cooling medium, it will be apparent that other liquids or even gases may be either heated or cooled, or be employed as a heating or cooling medium.

It should be understood that it is not desired to limit the invention to the exact details of construction and of operation herein shown and described, for various modifications within the scope of the appended claims may occur to persons skilled in the art.

It is claimed and desired to secure by Letters Patent:

1. In a cooler, a pair of helical tubular coils screwed one within the other and having their adjacent ends connected to form a single conduit beginning at an end of one of said coils and terminating at the adjacent end of the other coil, a cylindrical member located within and in close proximity to the innermost portion of said coils, and a tubu-

lar casing surrounding and located in close proximity to the outermost portion of said coils.

2. In a cooler, a pair of helical tubular coils screwed one within the other and having their lower ends connected to form a single conduit beginning at the upper end of one of said coils and terminating at the upper end of the other coil, a vertical cylindrical member located within and in close proximity to the innermost portion of said coils, and a vertical tubular casing surrounding and located in close proximity to the outermost portion of said coils.

3. In a cooler, inner and outer helical tubular coils of different diameter screwed one within the other and having their adjacent ends connected to form a single conduit beginning at an end of one of said coils and terminating at the adjacent end of the other coil, the outer diameter of the inner of said coils being greater than the inner diameter of the outer of said coils, a cylindrical member located within and in close proximity to the innermost portion of the inner of said coils, and a tubular casing surrounding and located in close proximity to the outermost portion of the outer of said coils.

4. In a cooler, inner and outer helical tubular coils of different diameters screwed one within the other and having their lower ends connected to form a single conduit beginning and terminating at the upper ends of said coils, the outer diameter of the inner of said coils being greater than the inner diameter of the outer of said coils, a vertical cylindrical member located in close proximity to the innermost portion of the inner of said coils, and a vertical tubular casing located in close proximity to the outermost portion of the outer of said coils.

5. In a cooler, a tubular casing, a cylindrical member axially within said casing and forming between them a conduit for a heat carrying medium, and a pair of helical tubular coils relatively screwed together throughout their length and having their adjacent ends connected to form a conduit for a cooling medium, said pair of coils being located within said first conduit and being located in close proximity to said casing and said member.

In testimony whereof, the signature of the inventor is affixed hereto.

JAMES WILSON.
